BRASSIERE

Sam Guberman, Bayonne, N.J., assignor to Maidenform,
Inc., New York, N.Y., a corporation of New York

Filed Aug. 20, 1964, Ser. No. 81,375

Term of patent 14 years

(Cl. D20—4)

The figure is a perspective view of a brassiere showing my new design, the portion of the back not shown is conventional and unornamented.

The characteristic feature of my design resides in the particular arrangement of the ornamented bands on the bust cups combined with the specific ornamentation shown thereon.

I claim:

The ornamental design for a brassiere, as shown and described.
